UNITED STATES PATENT OFFICE.

DAVID M. ROGERSON, OF JAMESTOWN, NEW YORK.

MOP-WRINGER.

SPECIFICATION forming part of Letters Patent No. 663,102, dated December 4, 1900.

Application filed February 12, 1900. Serial No. 4,903. (No model.)

To all whom it may concern:

Be it known that I, DAVID M. ROGERSON, a citizen of the United States, residing at Jamestown, in the county of Chautauqua and State 5 of New York, have invented a new and useful Mop-Wringer, of which the following is a specification.

My invention relates to improvements in mop-wringers in which the mop is passed between rollers attached to a mop-pail; and the 10 objects of my improvements are, first, to provide an adjustment as to the space between the rollers that they may be set and held at any desired point; second, to make the slots 15 in which the spring-roller is mounted on the angle of incline of the spring-pressure and avoid binding the roller; third, to provide a foothold for each foot at the bottom of the pail in correct position for holding the pail 20 while drawing the mop, and fourth, the combination and arrangement of the parts. I attain these objects by mechanism illustrated 25 in the accompanying drawings, in which--

Figure 1 is a plan view of my mop-pail and 30 mop-wringer. Fig. 2 is a sectional view of pail at line X X in Fig. 1, showing a side elevation of my wringer attached to the pail. Fig. 3 is a detail view of end bracket as attached to the pail at line Y Y in Fig. 1. Fig. 35 4 is a detail view of ratchet. Fig. 5 is a detail of end of locking bar and pin from under side. Fig. 6 is a sectional view at line Z Z in Fig. 1 with the adjustable frame raised. Fig. 7 is a detail plan view of locking-bar. Fig. 8 is a sectional view at line Z Z in Fig. 1 with the ends of the rollers removed to show the locking-bar in position holding the brackets.

Similar numerals refer to similar parts in 40 the several views.

10 is the mop-pail.

11 11 are footholds, which are shown in 45 about the correct position to hold the pail in drawing the mop through the wringer, and the form and method of attaching these angle-irons to the pail is shown in Fig. 2, although it would not be in correct position on line X X.

12 13 are rollers for compressing or wringing 50 the mop-cloth. Roller 12 is hung on screws 18 19 in inclined slots 16 17 in brackets 14 15. The slots are made at the angle of pressure

of springs 20 21, so that the roller will not bind in drawing the mop. The springs 20 21 are attached to screws 18 19 at one end and 55 to the brackets 14 15 at the other, as shown, spring 20 passing under bracket 14 to economize space.

24 is an adjustable frame which is hung on the raised wrists 25 25 on brackets 15 26 and 60 supporting-roller 13 on screws 22 23, screw 23 being countersunk to work inside of end bracket 15, as shown in dotted outline in Fig. 1. Frame 24 has ratchet-lever 28 and coil-spring 29 inserted in an opening therein, 65 and frame 24 extends down in lugs on each side of said opening to secure lever 28 by pin through the lugs and lever, so that the pressure of coil-spring 29 (see Fig. 4) on lever 28 above the pin may hold the lower end of lever 28 in the ratchet-teeth 31. Lever 28 has a projection on its lower end which works in ratchet-teeth 31 on curved ratchet-bar 30 on bracket 26. A light pressure on the upper end of lever 28 compresses spring 29 and releases the lower end of the ratchet-lever, allowing it to be raised or lowered and set in any one of teeth 31, which means of adjusting frame 24 allows roller 13 to be adjusted and held at any desired distance from spring-roller 70 75 12. (See Fig. 6.) It can thus receive any form of mop-head, no matter how thick or clumsy, and be adjusted to any mop in wringing. It allows of any degree of dampness in wringing, since the spring-ratchet sets the 80 85 rollers at any desired distance apart, and when thus set the mop can be wrung any number of times at exactly the same pressure. It is often desired to wipe off the floor with a semidamp mop and then go over it 90 with a dry mop. This is accomplished by raising frame 24, as shown in Fig. 6 and in dotted outline in Fig. 2, to the desired point, which draws roller 13 away from roller 12, where it is held by ratchet 28 30, and when 95 a stronger pressure is desired on the mop-cloth to wring it dry frame 24 is simply pushed down by the hand or foot.

Brackets 14, 15, and 26 extend above the top of pail 10 in order to bring the wringer-rolls 100 as high as possible and get the most room in the pail. This is accomplished with end bracket 15 by lugs 15' 15', which extend down into the pail and are fastened thereto, and with

brackets 14 26 by fastening the lower ends, as shown, and by ends 27 27 locking over and against the pail-rim, thus giving strength and rigidity to the brackets and pail.

5 In drawing large mops through the rollers there is sometimes a heavy strain on the ends of the rollers in brackets 14 26. I therefore attach a locking-bar 32 to adjustable frame 24 on wrist 33, which bar is shaped to turn 10 down under frame 24, as at 39 in Fig. 7, and extends across under the point of bracket 14 to pin 40. End 38 of bar 32 has an elongated opening 41, (see Figs. 5 and 7,) which is thus made to accommodate for any displacement. 15 Pin 40 is given a slight angle on side 42 in order that locking-bar 32 shall have a continuous draw on the pin and always hold tight. To arm 34 of bar 32 is attached spring 35, and the other end of spring 35 is attached 20 to projection 36 on frame 24, which spring operates bar 32. When handle 32' of bar 32 is raised and sprung forward, end 38 drops down out of the way and is held there by spring 35. The spring having passed down 25 over the center, as shown in Fig. 6, draws down on the locking-bar instead of up, as in Fig. 8. The mop can then be inserted and bar 32 sprung back to place, holding the brackets as one piece. Spring 35 thus holds bar 32 in 30 either position, because of its passing down over the center, and then drawing in the opposite direction.

It will be noticed that I mount only roller 12 in the inclined slots 16 17, and attach 35 springs thereto and that roller 13 is entirely free in its rotation.

I claim as new—

1. In a mop-wringer, a roller having suitable springs to give pressure thereto and suitable supports therefor, an adjustable frame 40

having suitable supports therefor, a roller mounted in said frame, a ratchet to adjust and hold said frame and roller, substantially as shown and described.

2. In a mop-wringer, an adjustable frame 45 supported on brackets and having a spring-ratchet for adjusting said frame, a roller supported in said frame, a second roller supported on brackets parallel to said first roller, springs attached to the roller-pins of said second roller to give a spring-pressure thereto, said roller-pins supported in slots made at the angle of the spring-pressure, as shown and for the purpose specified.

3. A mop-wringer having brackets provided with raised wrists, an adjustable frame hung on said wrists, a roller supported on said frame, a spring-ratchet for adjusting said frame, a spring-pressed roller supported on brackets and parallel to said frame-roller, 60 slots made in said brackets at the angle of the spring-pressure, a spring locking-bar on said adjustable frame and a projection on the opposite bracket to receive said bar, as shown and described.

4. In combination with a mop-pail having two footholds, a mop-wringer having a spring-pressed roller supported on brackets, an adjustable frame supported on brackets and having a roller mounted in said frame, a 65 spring-ratchet for adjusting said roller to said spring-pressed roller, substantially as shown and described.

In testimony whereof I have signed my name to this specification in the presence of 75 two subscribing witnesses.

DAVID M. ROGERSON.

In presence of—

N. E. THOMAS,
F. E. ARMITAGE.
